UNITED STATES PATENT OFFICE

WILLIAM E. ROSEL, OF COLUMBUS, OHIO, ASSIGNOR TO THE YARDLEY SCREEN & WEATHERSTRIP COMPANY, OF COLUMBUS, OHIO, A CORPORATION OF OHIO

CABLE LOCK FOR WINDOW BLINDS

Application filed June 25, 1929. Serial No. 373,671.

This invention relates to improvements in Venetian window blinds, that is, to that type of blind which is formed to include a plurality of longitudinally extending parallel slats or bars which are flexibly united and spaced by means of vertically extending ribbons or tapes, and wherein provision is made for collapsing or extending the blinds or tilting the individual slats to control passage of light through the blind into a room protected thereby.

In blinds of this type it is customary to raise and lower the same by means of flexible cables which pass around suitable pulleys or guides which are adapted to be manually grasped in order that forces may be applied permitting of the raising and lowering of the blind through the medium of the cables. Usually, the blinds are retained in a folded or partially folded or collapsed condition by passing the free end of the cable around a stationary supporting knob or other device positioned in connection with the window frame-work. This method, however, is open to numerous objections in that the knobs do not provide a secure device for retaining the blind in its desired position, the cable is apt to slip, causing the accidental lowering of the blind and, furthermore, the knobs tend to disfigure the window to which the blind is applied.

It is therefore an outstanding object of the present invention to provide automatic means in connection with the pulleys or guide devices around which the raising and lowering cable passes for the purpose of engaging with said cable so that when the latter is released, following operation of the blinds, the cable will be gripped to retain the blind in its desired position.

It is another object of the invention to provide a cable lock for use in the capacity stated which is entirely automatic, quick and efficient in operation and wherein slippage of the blind is rendered unlikely.

It is another object of the invention to provide a lock which is practically concealed from view and which is small, reliable and efficient in construction and service.

With these and other objects in view which

will appear as the description proceeds, the invention consists in the novel features of construction, combinations of elements and arrangements of parts hereinafter to be fully described and pointed out in the appended claims.

In the accompanying drawings:

Figure 1 is a front elevation of a portion of a Venetian blind provided with a cable locking means comprising the present invention.

Figure 2 is a vertical sectional view on the plane indicated on the line 2—2 of Figure 1,

Figure 3 is a detail sectional view taken through the cable lock on the line 3—3 of Figure 1 showing the cable when in a locked position,

Figure 4 is a similar view showing the cable in a released position permitting of the raising and lowering of the blind,

Figure 5 is a detail perspective view of the lock.

Referring more particularly to the drawings, the numeral 1 designates the frame-work of an ordinary window, and attached to the frame-work is a Venetian blind which is designated in its entirety by the numeral 2. The blind, as usual, comprises a longitudinally extending supporting bar 3 supported in a horizontal position in connection with the upper portion of the frame-work 1 by means of stationary brackets 4. Depending from the under side of the supporting bar 3 are brackets 5 which tend to effect the support of a rotatable tilting bar 6. This bar extends horizontally in parallelism with the bar 3 and is disposed immediately below the latter. The bar 6 carries depending ribbons or tapes 7 which effect the support of a plurality of horizontally extending slats 8, the lower ends of the ribbons 7 being connected with a bottom bar 9, the slats 8 being positioned in parallelism between the tilting bar 6 and the bottom bar 9.

To raise and lower a blind of this character, use is made of an operating cable 10. This cable has its free ends connected as at 11 with the bottom bar 9, the said cable passing upwardly through openings formed in the bar 9, the slats 8, the tilting bar 6 and the

supporting bar 3. The supporting bar 3 is grooved as indicated at 12 to receive the cable, and one end of this groove is provided with a pulley 13 arranged for rotation about a vertical axis 14.

Positioned upon the supporting bar 3 adjacent to the pulley 13 is a metallic plate 15, the latter being rigidly secured to the upper surface of the bar 3 by means of a screw or the equivalent 16. The plate 15 also acts to receive the shaft around which the pulley 13 rotates. The plate projects transversely of the bar and is formed to include a reduced overhanging portion 17 which projects some distance in advance or to the front of the bar 3. This overhanging portion 17 is of substantially inverted U form and is provided with a pair of spaced depending walls 18-18. These walls serve to receive for rotatable support a second pulley 19 which is rotatable about a horizontal axis 20, and the cable 10, after passing around the pulley 13, is trained around the pulley 19 and drops vertically along one of the sides of the blind 2, as shown especially in Figures 1 and 2.

As previously stated, it has been customary to train the free or lower end of the cable around a knob carried stationarily by the frame-work for the purpose of retaining the blind in an elevated or collapsed position. The present invention eliminates the use of such knobs and employs in lieu thereof an automatic lock for retaining the blind in a partially or fully elevated position. This is accomplished by the provision of a metallic frame 21 formed to include spaced vertical walls 22 arranged for engagement with the walls 18 and which are pivotally secured in connection with the walls 18 by the shaft 20 which constitutes the axis of the pulley 19. The walls 22 terminate in a flat lower wall 23 arranged substantially at right angles to the walls 22 and which connects the latter. The wall 23 includes an extension provided with a slot 24 through which the cable extends.

The upper portions of the walls 22 are slotted as at 25 for the reception of a shaft 26 which carries a locking roll 27, the walls 18 being slotted as at 28 for the movable reception of the shaft 26. The roll 27 is positioned immediately over the pulley 19 so as to be in a position to frictionally engage or grip the cable 10 as shown especially in Figure 3.

In operation, in order to raise the blind to a partial or fully collapsed position, the depending end of the cable is grasped and the necessary manual force applied by pulling downwardly on the cable to raise the blind.

When the blind has been thus raised to its desired position, the cable is released. This results in a tendency on the part of the cable to rest itself on the weight of the movable portions of the blind. This resting movement on the part of the cable causes its con-

tact with the roll 27, creating sufficient friction to draw the roll 27 toward the pulley 19, thus oscillating the frame 21 about its axis 20 with the result that the cable is gripped securely between the roll 27 and the pulley 19 preventing movement on the part of the cable and thus locking automatically the blind in its raised or partially raised position. If it is desired to lower the blind, the cable is grasped and pulled downwardly slightly. This results in drawing the cable tightly against the lower pulley 19 and as the lower end of the cable is grasped in the hand of the operator the blind may be lowered. As soon as the operator releases his grip on the cable the roll 27 becomes effective to lock the blind against further movement in a downward direction. It will thus be seen that the present invention provides an automatic cable guide especially adapted for Venetian blinds for performing easily and effectively the retention of the blind in any desired position of elevation.

What is claimed is:

1. A Venetian blind having a supporting bar and a plurality of flexibly connected parallel slats arranged below said bar, cables adapted to be manually operated for raising said slats to a collapsed or folded position beneath said supporting bar, locking means for said cable carried in connection with said supporting bar, said locking means including a horizontally journaled pulley over which said cables are trained, an oscillating frame having as its pivot the journal for said pulley and extending above and below the latter, a cable engaging roller carried by the upper end of said frame, and an extension formed with the lower end of the frame provided with an opening through which the free ends of said cables extend, whereby upon the manipulation and release of said cables to raise and lower the blind said frame will be rocked to bring the roller carried thereby into and out of binding engagement with the cables passing around said pulley.

2. A Venetian blind having a stationary supporting bar, a plate secured to said bar and provided with a pulley housing, a pulley journaled in said housing around which a slat operating cable is trained, a frame arranged adjacent said housing and pivoted to swing on the journal for said pulley, said frame extending above and below said pulley and formed with a lateral extension having an opening therein through which the free end of said cable projects, a cable engaging roller carried by the upper end of said frame, and means formed with said frame and housing for moving said roller towards said pulley into and out of clamping engagement with the cable passing around the pulley upon the rocking movement of said frame caused by the manipulation of said cable.

3. A Venetian blind having a stationary

supporting bar, a plate secured to said bar and provided with a pulley housing, a pulley journaled in said housing around which a slat operating cable is trained, a frame arranged adjacent said housing and pivoted to swing around the axis of said pulley, said frame extending above and below said pulley and provided with a laterally directed extension formed with an opening through which the free end of said cable projects, a cable engaging roller carried by the upper end of said frame, and vertically and horizontally arranged slots formed in said frame and housing through which the pivots of said roller extend, said slots serving upon the rocking of the frame to move said roller into and out of clamping engagement with the cable passing around said pulley.

4. A Venetian blind having a stationary supporting bar, a plate secured to said bar and provided with a pair of spaced depending sides, a pulley journaled between said sides and carried thereby and around which pulley a slat operating cable is trained, a frame arranged adjacent and exterior of said sides and pivoted to rock on the journal of said pulley, said frame extending a distance above and below said pulley provided with a lateral offset extension at its lower end having an opening through which the free end of said cable extends, vertical slots formed in said frame, horizontal slots formed in said sides, a cable engaging roller having its ends concealed within said slots whereby upon the rocking of said frame caused by the manipulation of said cable and due to the presence of said slots said roller will move into and out of engagement with the cable passing around said pulley.

40 In testimony whereof I affix my signature.
WILLIAM E. ROSEL.
